(57) **CLAIM**

The ornamental design for an inhalant dispenser, as shown and described.

DESCRIPTION

FIG. 1 is a front perspective view of an inhalant dispenser of our new design.

FIG. 2 is a rear perspective view thereof.

FIG. 3 is a top plan view thereof.

FIG. 4 is a bottom plan view thereof.

FIG. 5 is a front elevation view thereof.

FIG. 6 is a rear elevation thereof; and,

FIG. 7 is a first side elevation view thereof, the other side elevation view being a mirror image thereof.

The broken lines represent portions of the inhalant dispenser that form no part of the claimed design.
